(57) **CLAIM**

The ornamental design for a fabric panel scaffolding mount, as shown and described.

DESCRIPTION

FIG. 1 is a perspective view of the fabric panel scaffolding mount for supporting a channel on a scaffolding post.

FIG. 2 is a left side view of the fabric panel scaffolding mount in which the right side view of the fabric panel scaffolding mount is a mirror image of the left side view shown.

FIG. 3 is a top plan view of the fabric panel scaffolding mount in which the bottom view of the fabric panel scaffolding mount is a mirror image of the top plan view shown. FIG. 4 is a rear elevation view of the fabric panel scaffolding mount; and,

FIG. 5 is a front elevation view of the fabric panel scaffolding mount.

The broken lines in FIG. 4 illustrate portions of the fabric panel scaffolding mount and form no part of the claimed design.
